(57) **CLAIM**

The ornamental design for an electronic device storage case, as shown and described.

DESCRIPTION

FIG. 1 is a front elevation view of a storage case for an electronic device shown in a first position of use;

FIG. 2 is a top plan view thereof;

FIG. 3 is a bottom plan view thereof;

FIG. 4 is a right elevation view thereof;

FIG. 5 is a rear elevation view thereof;

FIG. 6 is a left elevation view thereof;

FIG. 7 is a front perspective view of the storage case for an electronic device provided in FIG. 1 and shown in a second position of use;

FIG. 8 is a rear perspective view of the storage case shown in the second position of use; and,

FIG. 9 is a rear perspective view of the storage case for an electronic device shown in a third position of use.

The broken lines showing environment are for illustrative purposes only and form no part of the claimed design.
